*Primary Examiner—Wallace R. Burke**Assistant Examiner—H. Baynham**Attorney, Agent, or Firm—Litman, McMahon & Brown***[57]****CLAIM**

The ornamental design for a carrier for mattress or box springs, as shown and described.

DESCRIPTION

FIG. 1 is a top plan view of a carrier for a mattress and box springs showing my new design;

FIG. 2 is a side elevational view thereof with the opposite side being a mirror image;

FIG. 3 is an end elevational view thereof with the opposite end being a mirror image; and

FIG. 4 is a top perspective view thereof; and

The broken lines showing of a mattress and stick figures are for illustrative purposes only and forms no part of the claimed design.

Fig. 4.**Fig. 1.****Fig. 3.****Fig. 2.**
